UNITED STATES PATENT OFFICE.

CLAY N. HEADDING, OF CHEHALIS, WASHINGTON, ASSIGNOR OF ONE-THIRD TO GEORGE A. HANSEN, OF CENTRALIA, WASHINGTON, AND ONE-SIXTH TO CHARLES B. HEADING AND ONE-SIXTH TO NEWTON J. HEADDING, BOTH OF CHEHALIS, WASHINGTON.

CAR-COUPING.

1,238,764.

Specification of Letters Patent. Patented Sept. 4, 1917.

Application filed August 17, 1916. Serial No. 115,430.

To all whom it may concern:

Be it known that I, CLAY N. HEADDING, a citizen of the United States, residing at Chehalis, in the county of Lewis and State of Washington, have invented new and useful Improvements in Car-Couplings, of which the following is a specification.

This invention relates to an improvement in car couplings, proposing a coupling of the general type shown in the patent to Schaeffer No. 567,866 of September 15, 1896.

The present coupling may be regarded as an improvement on the coupling shown in the Schaeffer patent referred to, and as such, its objects are to provide a coupling having all the advantages of the Schaeffer coupling and which moreover will be adaptable to extreme curves and will have a wider field of useful application, being capable of advantageous use by virtue of the improvements to be hereafter explained, on street cars, dump cars and logging trucks.

An embodiment of the invention is illustrated in the accompanying drawings, wherein:—

Figure 1 is a perspective view of the improved coupler;

Fig. 2 is a plan view, the pin being shown in section;

Fig. 3 is a longitudinal sectional view showing the pin in its inoperative position;

Fig. 4 is a longitudinal sectional view on the line 4—4 of Fig. 2 showing the pin in its operative position;

Fig. 5 is a perspective view of the pin-supporting head.

Similar characters of reference designate corresponding parts throughout the several views.

The coupling includes a draw head 1 having a mouth 2 in its end for the entrance of the link, said mouth having outwardly flaring side walls and opening into a chamber 3 located in the body of the draw head and extending rearwardly for an appropriate distance.

The coupling also includes a vertically movable pin 4, a link 5 and a supporting head 6 for said pin. The head 6 is disposed in the chamber 3, the bottom of which is stepped and includes a base 7 and a shelf or ledge 8 located in the rear of said base at an elevation slightly less than mid-way between

said base and the upper face of the draw head.

The chamber 3 communicates with an opening 9 in the upper face of the draw head (Figs. 1 and 2), which opening is normally closed by a removable dust guard or plate 10.

The head 6 has a forward portion of greater vertical depth or thickness than its rearward portion; and the under face of said head is of rearwardly and upwardly oblique form, as at 11. The enlarged forward portion of the head 6 rests upon the base 7 when the coupling is not in use and the oblique or cam face 11 engages the upper front edge of the ledge or shelf 8 whereby said ledge or shelf supports the rear portion of the head 70 and causes the head to have a generally forward and downward inclination. The head 6 is provided with a central forward extension or rib 12 which, when the coupling is not in use, engages under the lower end of 75 the pin 4, as shown in Fig. 3. The said pin, which has a round cross section, is slidable through alining vertical openings 14 and 15 which are located within the area of the flaring mouth 2.

In the use of the coupling, the link 5 is inserted in the flaring mouth 2 in the well known manner and ultimately engages the rib 12, the further inward movement of said link pushing the head 6 rearwardly until the 85 rib 12 passes from under the pin 4, at which time said pin drops, by gravity, through the openings 14 and 15 until its downward movement is arrested by the engagement of its headed upper end 16 upon the upper face of 90 the draw head. In connection with the rearward movement of the head 6 by the link 5, the forward end of said head is canted upwardly and ultimately comes to rest upon that portion of the link 5 which is disposed 95 in the rear of the pin 4. The weight of the forward portion of the head 6 on the link 5 tends to counter-balance said link and to hold it in a true horizontal positon so that it will freely enter an opposite draw head. 100

For the purpose of guiding the head 6 in its movements and of limiting the forward movement of the head when the link 5 is removed, the side walls of the chamber 3 are provided with perpendicular front shoulders 105 17 and with rearwardly and upwardly in-

clined rear shoulders 18; and the head is provided at its sides with triangular lugs 19 for coöperation with the shoulders 17 and 18. When the head 6 comes into its lowermost position, as indicated in Fig. 3 the lugs 19 engage the shoulders 10 at their lower ends; and during the rearward movement of said head, the lugs 19 ride along the shoulders 18 which also serve as a guide for said head in its forward and downward movement, *i. e.*, from the position shown in Fig. 4 to the position shown in Fig. 3.

The opening 14 for the pin 4 is located somewhat in advance of the chamber 3 which incloses the head 6 and is connected with said chamber and also with the opening 9 by a narrow slot 20 through which the rib 12 works.

I claim—

20. In a coupling, a draw head having a mouth provided with outwardly flaring side walls, alining vertical openings within the area of said mouth above and below the same, an internal chamber in the rear of said mouth

having an elevated ledge or shelf in the rear portion thereof, and a narrow slot extending between the upper of said vertical openings and said chamber, a pin of round cross section movable through said openings, a pin supporting head arranged within said chamber, said head having its forward portion of greater vertical depth than its rear portion and provided with a central forwardly projecting rib which extends through said slot for engagement under said pin when the latter is elevated, the rear portion of said head engaging said shelf, and means for supporting said head in the pin-supporting position thereof in a forwardly and downwardly inclined position.

In testimony whereof I have hereunto set my hand in presence of two subscribing witnesses.

CLAY N. HEADDING.
